UNITED STATES PATENT OFFICE.

FRITZ E. UTTMARK, OF BROOKLYN, NEW YORK.

MAILING-CARTON.

1,219,886.

Specification of Letters Patent. Patented Mar. 20, 1917.

Application filed May 12, 1916. Serial No. 97,002.

To all whom it may concern:

Be it known that I, FRITZ E. UTTMARK, a subject of the King of Sweden, and a resident of the city of New York, borough of Brooklyn, in the county of Kings and State of New York, have invented a new and Improved Mailing-Carton, of which the following is a full, clear, and exact description.

10 Among the principal objects which the present invention has in view are: to provide a resilient frame for absorbing blows incident to traffic, which otherwise would be imparted to the contents of the carton; to 15 provide a spiral wire frame adapted to be collapsed within confined limits; to provide a frame of the character mentioned with a permanent bottom and a removable top covering; to provide a top covering arranged to form a hinge member in conjunction with one of the convolutions of the wire frame; to form integrally with the said 20 cover, a guiding latch head; to provide a fabric covering for the said frame, said covering having a permanently closed end and a temporarily closed end concealing said cover; and to provide a mechanical fastening for said temporarily closed end and means integrally formed with said cover for 25 operating as an address tag.

Drawings.

Figure 1 is a perspective view, showing a carton constructed and arranged in accordance with the present invention;

Fig. 2 is a vertical section thereof;

Fig. 3 is a perspective view of the fabric covering, with which the carton is provided; and

40 Fig. 4 is a detail view, showing a sheet metal blank, from which the carton top is formed.

Description.

45 It will be understood that cartons constructed in accordance with the present invention are employed chiefly for the transhipment of glassware, or of articles of similar character dependent to a smaller or 50 larger degree upon some protective means for absorbing the shock of a blow liable to be imparted thereto in transportation. To this end, the carton is provided with a frame formed from a spiral spring wire 9. The

coil is cut to any suitable length and has 55 rigidly secured at one end thereof, to close the central space of the said coil, a disk 10. The disk 10 may be constructed from pasteboard or any other suitable material, and is fastened to the coil by means of loops 11. 60 The upper end of the frame formed by the wire 9 is normally closed by a pivoted cover cap 12.

The cap 12 is preferably constructed of sheet metal, for the formation of which a 65 blank, such as shown in Fig. 4 is provided. The disk-like body 13 of the cover cap has integrally formed therewith extensions 14 and 15. The extension 14 is shaped to form an inclined apron or guide, which passing 70 over the free end section 16 of the frame and the wire 9 thereof, permits the introduction of said section within a recess formed by the bend 17 in the neck 18 of the extension 14. To form the bend, the metal forming the extension 14 is scored on the lines 19. It will be understood that the metal forming the cap 12, is of as light a grade as is found desirable.

The extension 15 has a reduced end, which 80 will pass through a slot 20 formed in the body 13, as best shown in Fig. 4 of the drawings. It will be understood that prior to passing the reduced end of the extension 15 through the slot 20, the extension 15 is 85 wrapped under and bent around the topmost convolution of the spiral formed by the wire 9. In service the elongated reduced end of the extension 15 is passed between the uppermost convolution and the convolution adjacent thereto, to rest within the last-mentioned convolution, to form a rest for the said extension, which thereafter operates 90 as a slight spring to lift the cap 12, when the latch formed by the extension 14 is released 95 from the convolution of the wire 9, with which it is in service engaged.

The spiral frame thus formed is introduced in a fabric envelop 21. The envelop 21 fits the spiral formed by the wire 9 closely 100 and is preferably formed as a tube, the sides being lapped and glued or otherwise secured. As shown best in Fig. 3 of the drawings, one end of the envelop 21 is provided with a series of flaps 22. These in service 105 are folded one upon the other to form a multiple ply pad 23, which is shown best in Fig. 2 of the drawings. This pad is partic-

ularly useful if the carton and article contained therein are dropped so as to strike bottom end down. In this contingency, the shock is absorbed by the said pad and the 5 breakage of the contents of the carton which might otherwise ensue, is thereby prevented.

The opposite end of the tubular envelop 21 is provided with folding flaps 24, which 10 are oppositely disposed with the purpose to superpose one over the other. Diametrically opposite to the flaps 24, is a tab 25 and a tag 26. The tab 25 is provided with a T-shaped slot 27, as seen best in Fig. 3 of the 15 drawings.

The slot 27 may be opened to its full extent to receive the tag 26. The tag 26 has a reduced neck 28, the width whereof corresponds with the width of the cross head 29 20 of the slot 27. When the tag 26 is passed through the slot 27 and is drawn home, the neck 28 rests within the cross head 29 of the slot 27, while the extended sides of the tag overhang the edges of the tab 25 beyond the 25 ends of the cross head 29.

The tag 26 is constructed of any material suited to receive thereon a written address and a postage stamp 30. When thus arranged, it will be observed a package, such 20 as provided by the carton may be sent through the mails and by the parcel post department thereof. It will be observed that provision is thus made whereby the carton is secured in such manner as to permit the authorities to open the same without 35 destroying the carton or package.

Claims.

1. A carton comprising a hollow frame 40 constructed from an elongated wire coil; an end closure disk permanently attached to the convolution of said coil at one end thereof; and a removable cover for said frame pivotally attached to the end convolution of 45 said coil having a spring latch to operatively hold the end convolution of said coil upon which said cover is pivotally mounted, and at the opposite side thereof.

2. A carton comprising a resilient hollow 50 tube, said tube being bendable sidewise and compressible lengthwise; an end closure disk permanently attached at one end of said tube; and a removable cover for said tube pivotally connected therewith at the opposite 55 side end thereof.

3. A carton comprising a resilient hollow tube, said tube being bendable sidewise and compressible lengthwise; an end closure disk permanently attached at one end of said 60 tube; a removable cover for said tube pivotally connected therewith at the opposite end thereof; and means for removably locking said cover in closed position on said tube.

4. A carton comprising a resilient, com-

pressible hollow frame; an end closure disk permanently attached at one end of said frame; a removable cover for said frame pivotally connected thereto; and a pliable cover for said frame, said cover being permanently closed over one end of said frame and temporarily closed and mechanically held over the other end of said frame. 70

5. A carton comprising a resilient, compressible hollow frame; an end closure disk 75 permanently attached at one end of said frame; a removable cover for said frame pivotally connected thereto; a pliable cover for said frame, said cover being permanently closed over one end of said frame; a cover tab having a longitudinally disposed slot formed therein; and a locking member having a constricted neck portion and a widened tag portion adjacent said neck portion to extend beyond the edges of said slot. 80 85

6. A carton comprising a hollow frame constructed from an elongated wire coil; an end closure disk permanently attached to the convolution of said coil at one end thereof; a removable cover for said frame pivotally attached to the end convolution of 90 said coil having a spring latch to operatively engage the end convolution of said coil upon which said cover is pivotally mounted, and at the opposite side thereof; and a pliable cover for said frame, said cover being permanently closed over one end of said frame and temporarily closed and mechanically held over the other end of said frame. 95

7. A carton comprising a hollow frame constructed from an elongated wire coil; an end closure disk permanently attached to the convolution of said coil at one end thereof; a removable cover for said frame pivotally attached to the end convolution of 105 said coil having a spring latch to operatively engage the end convolution of said coil upon which said cover is pivotally mounted, and at the opposite side thereof; a pliable cover 110 for said frame, said cover being permanently closed over one end of said frame; a cover tab having a longitudinally disposed slot formed therein; and an address tag for said carton having a constricted neck portion adapted to rest within said slot to lock said tab in position to close the end of said frame. 115

8. A carton comprising a hollow frame constructed from an elongated wire coil; an 120 end closure disk permanently attached to the convolution of said coil at one end thereof; a removable cover for said frame pivotally attached to the end convolution of said coil having a spring latch to operatively engage the end convolution of said coil upon 125 which said cover is pivotally mounted, and at the opposite side thereof; a pliable cover for said frame, said cover being permanently closed over one end of said frame; 130

a cover tab having a longitudinally disposed slot formed therein; and an address tag for said carton having a constricted neck portion adapted to rest within said slot to lock
5 said tab in position to close the end of said frame, said tag being formed integrally with said cover.

In witness whereof I have signed my name to this specification in the presence of two subscribing witnesses.
